UNITED STATES PATENT OFFICE.

DOMENICO SIMONE, OF WASHINGTON, DISTRICT OF COLUMBIA.

RUBBER HEEL.

1,388,773.

Specification of Letters Patent. Patented Aug. 23, 1921.

Application filed September 30, 1919. Serial No. 327,516.

To all whom it may concern:

Be it known that I, DOMENICO SIMONE, a citizen of the United States, residing at Washington, in the District of Columbia, 5 have invented new and useful Improvements in Rubber Heels, of which the following is a specification.

This invention relates to improvements in elastic heels and has for an object the provision of a rubber heel which may be applied to a shoe without the use of cement.

Another object of the invention is the provision of a rubber heel having a relatively wide flat marginal flange surrounding its 15 upper surface, so as to provide a firm contact with the shoe, gripping the latter securely around the edges of the heel and providing suction means for initially gripping the shoe to permit of its being secured without 20 the use of cement for holding it in position preliminary to nailing.

A further object is the provision of a heel of this character which is slightly curved throughout its length, so as to increase the 25 degree to which the heel may be flexed to provide proper suction.

Other objects and advantages of the invention will appear as the following description is read in connection with the accompanying drawings.

In the drawings:

Figure 1 is a plan view of a heel embodying the present invention.

Fig. 2 is a sectional view on the line 2—2 of Fig. 1.

Fig. 3 is a similar view on the line 3—3 of Fig. 1.

Fig. 4 is a fragmentary elevation showing the heel in position for use.

Referring to the drawings in detail, wherein like characters of reference denote corresponding parts, the improved heel comprises a body portion 10, which as shown in Fig. 2 is curved throughout its length and is provided with a plurality of sockets 11 for the passage of nails or similar fastening devices for the purpose of securing the heel

in position upon a shoe. The upper surface of the heel, that is the surface which contacts with the shoe, is provided with a marginal flange 12, which extends along each side and at the back of the heel. This flange 12 is formed with a relatively wide upper surface and a right angular inner wall 13 and provides a concavity 14 in the upper surface of the body portion of the heel. The flange 12 at each end is beveled toward the inner end of the heel, as indicated at 15, the bevel extending inwardly and downwardly toward the center of the heel. After its application, 55 the under or tread surface of the heel is formed with a concavity, due to the flexing of the heel during its application, the surrounding edges of the concaved tread surface being comparatively broad, so that no 60 sharp edges result, which would tend to crumble and quickly wear away, causing a run over or uneven tread.

The invention is susceptible of various changes in its form, proportions and minor 70 details of construction and the right is herein reserved to make such changes as properly fall within the scope of the appended claim.

Having described the invention, what is claimed is:

An elastic heel comprising a solid body having a central portion adapted to engage a shoe and provided with a plurality of nail receiving sockets adjacent to the rear and sides of the lower surface of said body, and a relatively wide substantially U-shaped marginal flange surrounding the rear and sides of the upper surface of said body, adapted to engage a shoe and coöperating 85 with the central portion of the upper surface of said body to produce a concavity in the central portion of the lower surface of said body and a flat peripheral portion, said flange being provided with a right angular inner wall and having inwardly directed tapered outer ends.

In testimony whereof I affix my signature.

DOMENICO SIMONE.
